UNITED STATES PATENT OFFICE

2,654,222

DRIVE UNIT FOR DOMESTIC IRONING MACHINES AND THE LIKE

James F. Young, Erie, Pa., assignor to General Electric Company, a corporation of New York

Original application December 22, 1949, Serial No. 134,473. Divided and this application June 16, 1951, Serial No. 232,032

4 Claims. (Cl. 60—52)

1

This application is a division of my pending application, Serial No. 134,473, filed December 22, 1949, for Operating Mechanism for Domestic Ironing Machines and the Like.

The invention relates to domestic ironing machines of the flat plate type and, in particular, to an improved actuator for the pressing elements thereof.

Domestic flat plate ironing machines generally include a padded ironing table or buck on which the articles to be ironed are laid by the operator, and a heated shoe which is carried on an arm structure pivoted relative to the buck so that it can be brought into pressing position with relation thereto. By suitable mechanism, the respective elements are then brought together to press the articles therebetween. An ironing machine of this type is shown in Wardwell Patent 2,135,266, granted November 1, 1938, entitled "Ironing Press," and owned by the General Electric Company, assignee of the present application. In the Wardwell ironer, the shoe is moved manually and, as it approaches the ironing position, switch means are automatically closed to energize a hydraulic motor system which drives the buck upwardly against the shoe.

The object of my invention is the provision of improved means for automatically bringing together the buck and shoe to carry out the ironing operation.

Another object of my invention is the provision of pressure-operated valve means in the hydraulic motor system to govern the rate of rise and return of the pressing elements.

A further object of my invention is to provide adjustable by-pass means in the hydraulic system to obtain substantially uniform operation of the hydraulic actuator despite, for example, variations of viscosity of the liquid content of the system and subnormal line voltage at the operating motor.

In a presently preferred embodiment of my invention, I carry out these and other objects by providing, in my hydraulic motor unit, pressure-operated valve members which establish one rate of fluid flow for pressure application against the piston of the motor as the shoe is rising, and a more rapid flow rate for the return flow of fluid so as to speed the return of the motor piston, and, consequently, the return of the shoe and buck after the ironing operation. This rapid return is accomplished smoothly because of the dashpot action of the piston and cylinder. In addition, I provide a novel by-pass arrangement which can be adjusted to control the pressure

2

available on the underside of the piston, and thereby determine the rate of piston rise during the operation of the ironer.

In the accompanying drawing, Fig. 1 is a side elevation of an ironing machine showing the shoe and buck in retracted position; Fig. 2 is a top plan view of a piston head plate used in the hydraulic actuator, showing the pump cavity and valve outlet passages; and Fig. 3 is a sectional side elevation of the hydraulic motor unit embodying the present invention, the section being taken along lines 3—3 of Fig. 2.

Referring now to Fig. 1, the domestic ironing machine shown includes a frame structure 1 which is arranged in the form of a table having a rigid top 2 on which is mounted a cylinder 3, within which operates a hydraulic motor unit. As explained in detail hereinafter, said unit carries a buck 4 and is arranged to drive said buck upwardly to exert ironing pressure against a heated shoe 5, previously brought into operating position. The shoe 5 is carried by a rigid, substantially U-shaped, carriage 6, pivotally supported on a pair of pintles 7 which may be carried by hangers (not shown) extending from the cylinder 3. The cylinder is provided with a flange structure 8 disposed at an angle relative to the cylinder axis so as to support the cylinder in an angular relation with respect to the table top, as viewed in side elevation. The lower portion of the cylinder projects through an opening provided in the table top.

The shoe carriage 6 may be cushioned at the extremities of its travel toward or away from the buck by suitable means, such as the two pairs of springs 9 and 10 carried on rods 11 pivotally affixed beneath the table top 2 at opposite sides of the cylinder 3. Suitable adjustment nuts 12 and 13 are provided to regulate the tension of the springs, which bear against a pair of brackets 14 slidably mounted on the respective rods 11. Each bracket is pivotally attached to an arm 15 affixed to the carriage 6. It will be apparent that as the shoe arm rotates clockwise of Fig. 1, the spring 9 is compressed and that said spring may assist the return of the carriage. The spring 10 cushions the carriage at the end of its return movement. It should be understood that the buck and the shoe are elongate and of substantial area, and that each is symmetrical with respect to the cylinder 3. It should be further understood that the pairs of rods 11 and their associated springs and arms are preferably identical in size and shape. Referring now to Fig. 3, I mechanically drive

both the buck and the shoe carriage from a hydraulic motor device 16 disposed within the cylinder 3. Broadly speaking, the motor unit comprises a combination piston and pressure generator which pumps fluid into a space between the cylinder head and the piston head to drive the piston within the cylinder. The unit has a piston-like structure 17 having a compartment in which is mounted an electric motor 18, to the shaft of which is connected an impeller 19 operating within a pump chamber 20 of double involute form, provided by wall members or flanges 21 and 22, the latter being the actual piston head. The wall members 21 and 22 may be bolted together, as shown, and accommodate a piston ring 23. Other wall members or flanges disposed intermediate the ends of the piston 17 similarly provide a seat for a piston ring 24. A cap 25 is affixed to the end of the piston, and fixedly carries a frame 26 having outwardly extending members 27 (Fig. 1) on which the buck 4 is suitably mounted.

The cylinder 3 normally contains a charge of fluid, usually a light mineral oil, which occupies the cylinder to a level immediately below the upper piston ring flanges. The oil is in communication with the impeller pump chamber through apertures 28 and a pump chamber inlet 29. When the motor 18 is energized by any suitable electric circuit and switch, not shown, the impeller 19 generates hydraulic pressure which is discharged into a chamber 30 below the piston head, as presently explained. The hydraulic pressure reacts against the piston head to drive the piston 17 upwardly to propel the buck 4.

It is my belief that the operative connection between the piston means and the shoe carriage is best accomplished by a balanced linkage arranged for a centered, single point engagement with the carriage. Accordingly, in the illustrated presently preferred embodiment, I affix to the cap member 25 a strap 31 having diametrically opposed ends 32 extending through suitable slotted openings in the upper wall of the cylinder 3. To said ends 32, I pivotally affix the link members 33, which, in turn, are pivotally connected to an arcuate yoke structure 34, secured relative to the table top 2 by pivotal attachment to a pair of pintles 35 carried by brackets 36 thereon. Said yoke is, of course, symmetrical with respect to the piston structure 17, with one leg extending on each side of the cylinder 3 for pivotal engagement with pintles 35. A cross-bar 37 bridges the two legs of the yoke and extends beneath the shoe carriage 6, carrying a roller 38 supported by a pair of mounting brackets 39. The carriage 6 has a lower wall portion 40 provided with an elongate opening at its extremity, within which is a cam member 41 rigidly carried by brackets 42 for engagement by roller 38. Advantageously, as shown in Fig. 1, the end 43 of the cam may abut the top wall of the carriage 6 for securement thereto.

As explained in detail in my previously mentioned parent application, it is desirable in the operation of an ironing machine that the shoe be moved rapidly during the first portion of its relatively long path from its retractive to its operative position, during which time the buck should have a relatively short, slow movement. The rate of movement of the shoe preferably lessens as the shoe approaches ironing position, and the rate of rise of the buck desirably increases, with a minimum of extraneous load imposed on the buck at the time of actual pressing

so that the maximum fluid motor force is available. Since the motor piston moves relatively slowly within the cylinder at the beginning of the ironing operation, as more fully explained hereinafter, the initial rise of the buck is slow. The angular relation of the surface of the cam member 41, however, to the path of movement of the roller 38 is such as to translate the piston movement into an immediate relatively rapid rotation of the carriage 6. This is because the application of force of the roller 38 is initially substantially normal to the cam surface and, in view of the short lever arm between the point of engagement of the roller 38 with the cam 41 and the pivot point 7 of the carriage 6, the small rise of the roller effects a relatively great angular rotation of the carriage. It will be apparent from the shape of the face of the cam 41, that as the roller 38 is moved further in a clockwise direction, it will apply force at a rapidly decreasing angle to the cam surface and, consequently, will move the carriage 6 at a decreasing angular rate relative to its own movement. Consequently, the shoe carriage load on the hydraulic motor unit is rapidly reduced throughout the piston stroke, thereby making available more power for operation of the buck.

In my improved actuator for operating the buck and shoe in the manner described, the motor unit 16 within the cylinder 3 is controlled by valves 44, which slidably operate in channels 45 formed in plate 22 at the respective extremities of the involute pump chamber 20, as best seen in Fig. 2. The plate 22 is provided with apertures of markedly different diameter, large apertures 46 at the outermost ends of the grooves 45 so as to be actually externally of the pump chamber, and small apertures 47 substantially at the entrance end of said grooves. Apertures 46 provide direct communication between chamber 30 and the liquid reservoir. The valve members 44 may comprise plate-like elements in slidable engagement with the walls of the grooves 45 and the bottom of plate 21, so as to have a substantially leak-proof association with said walls. Spring members 48 bias the valves to occupy a normal position which exposes the openings 46 and covers openings 47. At the instant of operation of the impeller 19, therefore, the hydraulic fluid has no escape from the impeller chamber, and its first action is to drive the valve members 44 along the channels 45 until the openings 47 are uncovered, whereupon the hydraulic fluid enters the chamber 30. The hydraulic unit drives the piston upwardly at the rate determined by the rate of flow of liquid through the discharge openings 47. The governing effect of the restrictions to the impeller discharge provided by these openings make the operation of the motor unit substantially uniform throughout a motor voltage range of from 90 to 130 volts. It should be understood that the openings 46 are closed by the valve members 44 when the latter have opened the ports 47, thus preventing any by-passing of hydraulic pressure through openings 46 to the reservoir above the piston head. After the pressing operation has been completed, the operator opens a switch, not shown, to de-energize motor 18, and the springs 48 drive the valve members 44 so that the relatively large ports 46 are exposed and the weight of the buck causes the piston unit 17 to move downwardly, oil returning to the cylinder above the piston head through the passages 46. Springs 9 keep the shoe carriage in engagement with the cam

roller 38 until the over-center gravity position of the shoe and carriage is reached, following which such engagement is inherently maintained. The dashpot effect of the oil ports 46 and of the piston and cylinder is thus available to smooth the return movement of the shoe as well as of the buck. The buck rises slowly during its initial movement, and is accelerated during its upward travel as the load imposed on the motor unit by the shoe and carriage is lessened, in the manner previously explained.

Adjustable speed control of the piston and other operating advantages may be accomplished by the inclusion of a pressure by-pass system with cylinder 3, arranging the system so that its downstream end enters the cylinder at a point coinciding with the position of the piston when the shoe has reached its operating position, so that upon further motion of the piston equal pressure will be applied to both sides of the by-pass valve element to neutralize its effect. When this occurs, maximum fluid pressure will then be available for the actual ironing operation and will depend upon the capacity of the fluid pump, without regard to the setting of the by-pass valve.

Referring again to Fig. 3, a suitable relief valve organization is shown, including a valve body 49 shaped to the curvature of the cylinder and welded or otherwise secured thereto in leakproof relationship. The valve body is bored to provide a flow circuit comprising the interconnected upstream and downstream legs 50 and 51 which communicate with the cylinder, as shown. A sleeve 52 is fixed to the valve body in pressure-tight relationship therewith; said sleeve to be internally threaded to receive the valve stem guide member 53 within which slidably operates a poppet type valve 54 biased by a spring 55 into seated relationship with respect to the passage 50. By means of a suitably affixed adjustment knob 56, the member 53 may be rotated for movement axially within sleeve 52, so as to establish a desired spring bias against the valve 54.

It will be noted from Fig. 3 that with the piston in home position, the upstream passage 50 is blocked from communication with the chamber 30 by the respective piston elements 21 and 22. Initially, therefore, the fluid pressure is available at its maximum level to overcome the starting inertia of the operating elements. The cam drive of the shoe carriage effects maximum rotation of the carriage toward its operating position during the very early stages of piston lift, thereby requiring considerable force to be delivered to the links 33. Therefore, by the time the upstream passage 50 is sufficiently cleared by the piston head to become operatively effective, the shoe carriage will have completed the greater portion of its travel. By suitable adjustment of the valve bias, the operator may control the rate of movement of the buck and of the shoe during the latter portion of the shoe travel and during the greater portion of the buck travel to their respective operating positions. For example, by reducing the spring bias, a considerable portion of the oil discharging through the ports 47 may be by-passed above the piston head, thereby effectively slowing the piston drive. Conversely, by increasing the spring bias, one may appropriately reduce oil flow through the by-pass structure. In any event, it should be noted that if at any instance before the piston head assembly covers the downstream passage 51 any normal restraint against the movement of the shoe carriage or buck develops; for example, by the op-

erator in an emergency seeking to hold back the shoe while leaving the electric motor 18 energized, the hydraulic pressure within the chamber 30 will be expended by passing through the 5 by-pass circuit and the ironer will not be exposed to damaging strains. Thus, the by-pass structure serves as a pressure relief means. After the piston has risen fully, at which time the shoe is in ironing position, the downstream port 51 10 is closed by the piston head and the balance of pressure on each side of the valve 54 becomes equal, making full pressure available against the piston head 22 for exertion of ironing pressure.

While I have shown a particular embodiment of 15 my invention, it will be understood, of course, that I do not wish to be limited thereto, since many modifications may be made; and I, therefore, contemplate by the appended claims to cover any such modifications as fall within the true spirit 20 and scope of my invention.

What I claim as new and desire to secure by Letters Patent of the United States is:

1. A power unit for an ironing machine or the like, comprising a cylinder and a combined piston and hydraulic pressure generation means therein, including a hollow piston structure having extending flange means providing a piston head and piston ring securing means, a pump disposed within said flange means, said flange 25 means defining a chamber for said pump with rectilinearly extending outflow passages, said passages having pump discharge ports extending through said piston head for discharging liquid 30 forwardly of said piston head to propel the piston, means providing a reservoir of liquid within said cylinder to supply said pump, motor means within said cylinder to operate said pump, means defining normally open apertures through said 35 flange means communicating directly between said reservoir and the space forwardly of said piston head to return liquid to said reservoir upon return movement of said piston means, valve members slidably within said outflow passages to close said return flow apertures and open said 40 discharge ports during pump operation, and biasing means for said valve members to close 45 said ports and open said return flow apertures upon cessation of pump operation.

2. A power unit for an ironing machine or the like, comprising a cylinder and a combined piston and hydraulic pressure generation means therein, said means including a hollow piston structure having piston ring means engaging with the cylinder wall, a pump disposed within said structure, motor means within said cylinder for driving said pump, means affording a reservoir 55 of liquid to be drawn by said pump, an outlet passage from said pump, said passage having a discharge port for discharging oil forwardly of said 60 piston to propel the piston, means defining a normally open aperture through said piston structure into said cylinder for returning the discharged oil directly to the reservoir on return movement of said piston, valve means disposed 65 within said pump outlet passage and responsive to pump discharge pressure to close said return passage means during pump operation, and means biasing said valve to open said return passage means upon cessation of pump operation.

3. A power unit for an ironing machine or the like, comprising a cylinder having a combined piston and hydraulic pressure generation means therein, said means including a hollow piston structure having piston ring means engaging 70 with the cylinder wall to divide said cylinder into

a pressure chamber and a reservoir chamber, a pump disposed within said structure, motor means within said cylinder for driving said pump, means affording communication of liquid from the reservoir chamber to said pump to be drawn by said pump, an outlet passage from said pump, said passage having a discharge port for discharging liquid into said cylinder pressure chamber to propel the piston, a normally open return port through said piston structure for liquid flow directly from said pressure chamber to said reservoir chamber on return movement of said piston, valve means disposed within said pump outlet passage and responsive to pump discharge pressure to close said return port during pump operation, means for biasing said valve to open said return port upon cessation of pump operation, and an adjustable pressure by-pass system effective during a portion of the piston power stroke to return some of the liquid discharged into said pressure chamber to the reservoir chamber to limit the liquid pressure effective for moving the piston.

4. A power unit for an ironing machine or the like having a cooperating buck and shoe, comprising a cylinder and a combined piston and hydraulic pressure generation means therein, including a hollow piston structure having extending flange means providing a piston head and piston ring securing means dividing said cylinder into a pressure chamber and a reservoir chamber, a pump disposed within said flange means, a chamber for said pump defined by walls

5
